TELEPHONE SYSTEM.

1,016,617.

Specification of Letters Patent.

Patented Feb. 6, 1912.

Application filed May 10, 1909. Serial No. 495,104.

To all whom it may concern:

Be it known that I, WILLIAM A. FRICKE, citizen of the United States, residing at Chicago, in the county of Cook and State of Illinois, have invented a certain new and useful Improvement in Telephone Systems, of which the following is a full, clear, concise, and exact description, reference being had to the accompanying drawings, forming a 10 part of this specification.

My invention relates to telephone exchange systems, and particularly to that class of telephone exchange systems in which a common or central source of energy is employed at the exchange for operating the line signal and which source of current is normally connected with the telephone line, whereby the line signaling apparatus may be operated when the switch-hook is elevated or 15 operated upon the removal of the telephone receiver. In accordance with my invention, I provide at such calling station a normally continuous metallic conductor of high resistance and serving to unite the sides of the 20 telephone line, a signal-receiver being included or associated with said high resistance conductor, the resistance of the high resistance conductor serving to prevent the 25 operation of the line signaling apparatus when the conductor controlled by the switch-hook is open, a source of uni-directional current being associated with the telephone line and which is coöperatively related with 30 switching mechanism at the exchange that serves to bring said source of uni-directional current into circuit relation with the telephone line to operate the signal-receiver at 35 the telephone station.

Another feature of my invention relates 40 to party telephone lines. In one embodiment of the invention as applied to party telephone lines, I employ two party line telephone stations equipped as above described, the signal-receiver at one party line station 45 being responsive only to signaling current of negative sign from said source of uni-directional current, while the other signal-receiver is adapted to respond to current of positive sign, the switching mechanism serving 50 to direct current of proper sign to the selected one of the signal-receivers. In another embodiment of my invention, I also associate with the party telephone line an additional telephone station having a signal-receiver that is responsive only to alter-

nating current. In another embodiment of the invention, I provide a fourth station, in which the signal-receiver is included in a grounded conductor extending from a mid portion of a high resistance conductor in 60 bridge of the sides of the telephone line, this latter signal-receiver being also responsive to current from the source of uni-directional current.

The accompanying drawing diagrammatically shows the preferred form of my invention as applied to a four station party line which is diagrammatically illustrated in connection with a diagrammatically illustrated exchange.

I have shown my invention as applied to a party telephone line upon which there are four telephone stations, though I do not wish to be limited to the number of telephone stations that are to be associated with the line. At each of the telephone stations A, B and C, I have indicated a signal receiver, the telephonic apparatus being omitted at stations A, B, C, as the illustration thereof is not necessary to an understanding 70 of the invention. At the party telephone line station D, however, I have indicated a telephone transmitter *a*, a telephone receiver *b*, and a switch-hook *c*, the switch-hook, when supporting the telephone receiver, opening the bridge between the sides *d* and *e* of the party telephone line, said bridge including the transmitter *a* and the telephone receiver *b*, the switch-hook, when relieved of the weight of the telephone receiver *b*, establishing such bridge. The telephonic apparatus at each of the stations A, B, C may be similar to that illustrated at the station D, and may have similar circuit relation 75 with the sides of the party line the circles *a*¹ indicating the location of the telephonic apparatus. The sides *d*, *e* of the party telephone line are shown as extending to a multiple switch-board, said sides terminating in line-jacks *f* *f* and an answering-jack *g*. It is to be understood, however, that I do not 80 limit myself to multiple switch-board practice. Suitable signal appliances, including the line-relay *h* and the cut-off relay *i*, are shown in association with the party telephone line in a manner which is well understood by those skilled in the art. Cord-connecting apparatus, in this instance including 85 an answering-plug *k* and a calling or connecting-plug *l*, is shown, whereby a party tele- 90

95

phone line may be connected with another telephone line, but it is to be understood that I do not limit myself to a cord-connecting outfit employing a plurality of plugs. In 5 the system illustrated, I have shown a well-known form of supervisory apparatus associated with the answering and connecting ends of the cord-circuit, this supervisory apparatus including a calling subscriber's relay *m*, a calling subscriber's supervisory lamp *n*, a called subscriber's supervisory relay *o*, and a called subscriber's signal lamp *p*. Further description of the supervisory apparatus will be unnecessary, as the drawing 10 clearly indicates the relation thereof to the cord-circuit.

Four calling keys are shown in association with the connecting end of the cord-circuit, key *A*¹ corresponding to the signal-receiver *q* at station A, key *B*¹ corresponding to the signal-receiver *r* at station B, key *C*¹ corresponding to the signal-receiver *s* at station C, and key *D*¹ corresponding to the signal-receiver *t* at station D. The 15 signal-receiver *q* at station A is in bridge between the sides *d*, *e* of the party line, the bridge including the signal-receiver *q* desirably possessing one thousand ohms resistance, which is preferably disposed substantially 20 entirely upon the signal-receiver *q*. The bridge containing the signal receiver *q* desirably also includes a condenser *q*², so that direct current will not be permitted to pass through the signal-receiver *q*. The key *A*¹, when operated, includes a 25 source of alternating current *q*² in serial relation with the sides *d*, *e* of the party line (assuming the calling-plug *l* engages one of the jacks of said party line), the signal-receiver *q* being constructed to respond to the 30 alternating current emanating from the generator *q*², which preferably furnishes current at ninety volts pressure, to which end said signal-receiver, which is preferably 35 a signal-bell structure, includes a polarized operating electro-magnet constructed similarly to the operating electro-magnets of signal-bells found at subscribers' stations. The source of direct or uni-directional current *u* at the central exchange, which preferably furnishes current at one hundred forty volts pressure, is adapted to have varying associations with the party line through the instrumentality of the keys 40 *B*¹, *C*¹, *D*¹, the key *B*¹ serving to connect the positive side of the battery *u* with the lower side *e* of the party line and the negative side of the battery with the upper side *d* of the party line, whereby the signal-bell 45 *r* of station B, which is included in a bridge that it itself controls, is subject to the action of direct current of positive sign to which said signal-bell is adapted to respond, direct current of positive sign 50 causing the armature of the signal-bell *r*

to move in a clockwise direction, said armature, as a consequence of this movement, thereafter breaking, at *r*¹, the bridge including the signal-receiver *r*, the bridge being maintained closed at *r*¹ a sufficient 70 length of time to permit the armature in its clockwise movement to sound the bell. After the circuit is broken at *r*¹, the spring *r*² mechanically returns said bell-armature to its original position, by moving said armature in a counter-clockwise direction, and again causes the bell to sound, the bell structure including two gongs between which the clapper *r*³ carried by the armature, oscillates. In order that the signal-receiver *r* may respond to current of positive sign, it is properly polarized. The signal-receiver *s* at station C is desirably of a construction that is identical with the signal-receiver at station B, with the exception 75 that the signal-receiver at station C is polarized to respond to current of negative sign when the key *C*¹ is actuated, the key *C*¹ serving to connect the negative pole of the battery *u* with the side *e* of the party line 80 and the positive pole of said battery with the side *d* of the party line, the keys *B*¹, *C*¹ thus serving, one to connect the battery with the party telephone line *d*, *e* in one direction, and the other to connect said battery with said party telephone line in the 85 reverse direction.

It will not be necessary to describe the component parts and the circuit relations of the signal-receiver *s*, the circuit relations of the receivers *r* and *s* being identical, each signal-receiver being included in a bridge whose continuity is controlled thereby, the two receivers having, as stated, no distinctions so far as their circuit relations 90 are concerned, the only distinction being in their polarization, the receiver *r* responding to current of positive sign and the receiver *s* responding to current of negative sign. 100

The construction of the signal-receiver *t* is preferably identical with the construction of the signal-receivers *r* and *s*, but its circuit relation with the party telephone line is different from the circuit relation of the 105 signal-receivers *r* and *s* of the party telephone line. The signal-receiver *t* may be arranged to respond to current of positive or negative sign, the signal-receiver *t* in the arrangement shown being adapted to respond to current of positive sign. The circuit arrangement of the signal-receiver *t* differs from the circuit arrangement of the signal-receivers *r*, *s*, in that with the arrangement of the signal-receiver *t* the signaling current is caused to pass over but one of the sides *d*, *e* of the party line (in this instance the side *e*), the current being returned by a third conductor whose continuity is established when the key *D*¹ is 110 115 120 125 130

actuated, this third conductor preferably including the ground connections v .

My invention, in one of its aspects, relates particularly to common battery or central energy systems, in which a battery w is employed for signaling purposes. I have shown a common battery w which is not only adapted for signaling purposes, but may also be adapted, if desired, to supplying the transmitters a at the party line stations with talking battery current. The common battery w is normally connected in circuit relation with both limbs d, e of the party telephone line, whereby a subscriber at either of the stations A, B, C, D, in taking his telephone receiver from its switch-hook, in order to signal the operator, completes circuit for said battery w at his switch-hook by closing the low resistance conductor including the telephone receiver, said battery w , owing to its relationship with the line and the relay h occasioning the operation of the party telephone line signal x . The inter-relation of the battery w , the relays h and i , the line-signal x , and the cord-connecting outfit, is well illustrated, and is well known to those skilled in the art and needs no further description. The central source of energy w , also, in the embodiment of the invention illustrated, supplies the transmitter a at a calling party line station with current. The condenser q^1 in the bridge at station A which includes the signal-receiver q , serves to prevent the passage of direct current from the battery w through said bridge, and also serves to prevent the passage of direct current from the battery u when applied to the line by means of either of the keys B^1, C^1 .

The signal-receivers r and s at stations B, C are included in bridges which are metallically continuous, in order that current from the source u may operate said signal-receivers. In order to reduce the flow of current from the battery w across the bridges including the signal-receivers r and s , which bridges are normally closed, said bridges are made of very high resistance, resistances w^1 being included in said bridges, which are desirably of forty-four thousand ohms each, the magnets of the signal-receivers r and s being each desirably wound to six thousand ohms. The signal-receiver t includes an electro-magnet which is also desirably wound to six thousand ohms resistance, the ground connection from the side e of the party telephone line including a very high resistance y , which is preferably of forty-four thousand ohms. In order to balance the party line, a resistance y^1 at station D is connected with the ground v at station D, the circuit for the signal-receiver t including a connection which is common to the inner terminals of the resistances y, y^1 , this connection extending to the ground v at station D, through the magnet of the signal-

receiver t , the armature of said signal-receiver and the contact t^1 in normal engagement with said armature. As the party telephone line is thus connected by the resistances y, y^1 , another closed path is normally present for completing circuit for the battery w . The resistances y, y^1 together, in the preferred embodiment of the invention, aggregate eighty-eight thousand ohms, and the resistances in each of the bridges at stations B, C each includes fifty thousand ohms of resistance, so that though there are several conductors in metallic bridge of the party telephone line at the party line stations that establish circuit for the battery w , said conductors are of such high resistances as to make the flow of current from the battery w over the line when the line is not in use, negligible, as will be readily understood by those skilled in the art, particularly when it is remembered that the source of current w preferably is a twenty-four volt battery. If the battery w is grounded, and it is preferred to ground said battery at w^2 , the ground v at station D will not cause an excessive flow of current from the battery w when the party telephone line is idle, inasmuch as the grounded circuit for the battery w , including the ground w^2 and the ground v at station D, includes the high resistance y^1 . Thus all of the paths that are closed to current from the battery w at the party line stations B, C, D are of such high resistance, that though these paths are in multiple relation with the battery w , the flow of current from said battery is so small, when the line is idle, as to be unobjectionable from a practical commercial standpoint.

While I have herein shown and particularly described the preferred embodiment of my invention, I do not wish to be limited to the precise arrangement shown, as changes may readily be made without departing from the spirit of my invention, but,

Having thus described my invention, I claim as new and desire to secure by Letters Patent the following:—

1. A common battery telephone exchange system including a telephone line extending from two telephone stations to an exchange; a conductor of high resistance in bridge of the line at each telephone station; polarized signal receivers in said high resistance conductors that are responsive to uni-directional current of opposite polarity; switching mechanism at the exchange for effecting the passage of uni-directional current over the line in different directions suited to the signal receiver that is to be operated; signaling apparatus and a source of current at the exchange adapted for inclusion in circuit with the line, the exchange signaling apparatus being prevented from operating by the high resistance conductors at the aforesaid stations; and a conductor

- of low resistance at each of said stations governed by the switch hooks thereat and opened when the switch hooks support the telephone receivers and closed when the 5 switch hooks are free of the telephone receivers to shunt the high resistance bridge conductors and thereby occasion the operation of said exchange signaling apparatus.
2. A common battery telephone exchange 10 system including a telephone line extending from two telephone stations to an exchange; a conductor of high resistance in bridge of the line at each telephone station; polarized signal receivers in said high resistance 15 conductors that are responsive to uni-directional current of opposite polarity; switching mechanism at the exchange for effecting the passage of uni-directional current over the line in different directions suited 20 to the signal receiver that is to be operated; a third telephone station to which the telephone line extends; a high resistance bridge conductor at this third telephone station; a grounded connection from an intermediate 25 portion of this high resistance conductor; a signal receiver included in this grounded connection; means at the exchange for including a source of signaling current in grounded circuit with the signal receiver at 30 the third station; signaling apparatus and a source of current at the exchange adapted for inclusion in circuit with the line, the exchange signaling apparatus being prevented from operating by the high resistance 35 conductors at the aforesaid stations; and a conductor of low resistance at each of said stations governed by the switch hooks thereat and opened when the switch hooks support the telephone receivers and closed 40 when the switch hooks are free of the telephone receivers to shunt the high resistance bridge conductors and thereby occasion the operation of said exchange signaling apparatus.
- 45 3. A common battery telephone exchange system including a telephone line extending from a telephone station to an exchange; a conductor of high resistance in bridge of the line at the telephone station; a signal 50 receiver in said high resistance conductor; a second telephone station to which the telephone line extends; a high resistance bridge conductor at this second telephone station; a grounded connection from an intermediate 55 portion of this high resistance conductor; a signal receiver included in this grounded connection; means at the exchange for including a source of signaling current in grounded circuit with the signal receiver at 60 the second station and a source of signaling current in metallic circuit with the signal receiver at the first station; signaling apparatus and a source of current at the exchange adapted for inclusion in circuit with 65 the line, the exchange signaling apparatus

being prevented from operating by the high resistance conductors at the aforesaid stations; and a conductor of low resistance at each of said stations governed by the switch hooks thereat and opened when the switch 70 hooks support the telephone receivers and closed when the switch hooks are free of the telephone receivers to shunt the high resistance bridge conductors and thereby occasion the operation of said exchange signaling apparatus.

4. A common battery telephone exchange system including a telephone line extending from two telephone stations to an exchange; a conductor of high resistance in bridge of the line at each telephone station; polarized signal receivers in said high resistance conductors that are responsive to uni-directional current of opposite polarity; the signal receivers at the aforesaid stations being included in circuit with switches that are provided with means for normally closing these signal receiver circuits and which switches are operated by the signal receivers to open the signal receiver circuits; switching mechanism at the exchange for effecting the passage of uni-directional current over the line in different directions suited to the signal receiver that is to be operated; signaling apparatus and a source of current at the exchange adapted for inclusion in circuit with the line, the exchange signaling apparatus being prevented from operating by the high resistance conductors at the aforesaid stations; and a conductor of low resistance at each of said stations governed by the switch hooks thereat and opened when the switch hooks support the telephone receivers and closed when the switch hooks are free of the telephone receivers to shunt the high resistance bridge conductors and thereby occasion the operation of said exchange signaling apparatus.

5. A common battery telephone exchange system including a telephone line extending from two telephone stations to an exchange; a conductor of high resistance in bridge of the line at each telephone station; polarized signal receivers in said high resistance conductors that are responsive to uni-directional current of opposite polarity, the signal receivers at the aforesaid stations being included in circuit with switches that are provided with means for normally closing these signal receiver circuits and which switches are operated by the signal receivers to open the signal receiver circuits; switching mechanism at the exchange for effecting the passage of uni-directional current over the line in different directions suited to the signal receiver that is to be operated; a third telephone station to which the telephone line extends; a high resistance bridge conductor at this third telephone station; a grounded connection from an inter- 11 12 13

mediate portion of this high resistance conductor; a signal receiver included in this grounded connection; means at the exchange for including a source of signaling current in grounded circuit with the signal receiver at the third station; signaling apparatus and a source of current at the exchange adapted for inclusion in circuit with the line, the exchange signaling apparatus being prevented from operating by the high resistance conductors at the aforesaid stations; and a conductor of low resistance at each of said stations governed

by the switch hooks thereat and opened when the switch hooks support the telephone receivers and closed when the switch hooks are free of the telephone receivers to shunt the high resistance bridge conductors and thereby occasion the operation of said exchange signaling apparatus. 15

In witness whereof, I hereunto subscribe my name this 8th day of May A. D., 1909.
